Nathaniel Adams.

9588X

The schedule referred to in these letters Patent and making part of the same, containing a description in the words of the said Nath. Adams himself, of his Improvement in making Bricks:

Specification of an improved mode of moulding bricks by a machine to be worked by steam or other power. The object had in view in this improvement is principally facility in the manufacture of bricks. The moulds are to be placed on a horizontal wheel of iron or other material 8 feet in diameter which turns upon an upright shaft inserted in a strong frame which moulds are to be sufficient in size to admit clay for four or more bricks. For depositing and pressing the clay in the moulds the following machinery is used 1st a Box for the reception of the clay directly over the moulds the lower part of circular form in width corresponding with the length of the moulds at the bottom of which box apertures a little less than the size of the bricks to be made to admit the passage of the clay into the moulds and over which apertures be used a screen of large wire to exclude coarse particles from the moulds. 2^d a horizontal shaft of iron through the centre of this Box with leaves of the same materials in length equal to the width of the box, jointed in such manner on the shaft that in the revolution upwards through the clay very little resistance to the shaft is opposed the leaf being then depressed downwards but in the revolution downwards the leaf being brated by an arm so as not to yield beyond a certain point the clay under it is pressed along until it reaches the apertures aforesaid. 3^d a vertical rag wheel on the end of this horizontal shaft outside of the Box into which a dog moved by a crank catches and thus causes the revolution of the shaft. The horizontal wheel is moved by another dog which pushes a rag wheel attached to the horizontal wheel and having a notch for each mould, which dog is also attached to the same crank just mentioned - which arrangement of the dogs and rag wheels operates to move the vertical and horizontally wheels alternately.

so that when by the movement of the horizontal wheel the mould is brought under the apertures of the clay box, that wheel then remains stationary and the vertical wheel revolves and forces the clay into the moulds - which being filled, the horizontal wheel is again put in motion and removes the moulds. The crank it is intended shall be moved by steam power as the cheapest and most expeditious, but any other power can of course be applied with equal convenience.

4th valve to permit the clay escaping upwards, when too large a quantity has been brought upon the mould, while at the same time by attaching a weight, a sufficient quantity of the clay will be always forced into the moulds. 5th valve under each aperture of the clay box before mentioned to permit the passage of the mould in case any hard substance should have been mixed with the clay and protrude above the mould. In the annexed drawing A.A. represents the large horizontal wheel a.a. the vertical shaft in which it turns and b.b. are moulds, similar ones to which are to be contained in all the other spaces represented in the wheel. B.B. is the clay box which is represented open in order to shew the interior. d.d. are two wings in the horizontal revolving shaft intended to press the clay down to the grated aperture C. f is a dog attached at or to a crank, and which catching in the dogs or notches of the vertical cog wheel, withdraws it round thus causing a revolution of the shaft and leaves within the clay box, while by the small crank the dog g is pressed against notches in the horizontal wheel thus causing an alternate movement of the horizontal and vertical wheels by which the moulds are successively brought under the aperture C, and the clay then forced into them. C is the valve or regulator of the pressure on the clay in the mould, a weight being attached to the crank i the valve is held down and thus the clay prevented from escaping upwards until the pressure exceeds the weight. K is the valve or set of valves which are intended to open when any large hard substance mixed with the clay protrude above the mould.

I claim as my invention the combination of the parts of said

53.

machine in the manner above described, or in any other manner substantially the same for the purposes aforesaid. - But I do not claim any one of those parts separately, or independently of the combination.
